US00D692408S

(12) **United States Design Patent**
Dugger et al.

(10) **Patent No.:** US D692,408 S
(45) **Date of Patent:** ** Oct. 29, 2013

(54) **WIRING FOR DIGITAL MEDIA PLAYERS**

(76) Inventors: **Frank Emanuel Dugger**, Honolulu, HI (US); **Yumi Fujiwara Benedicto-Dugger**, Honolulu, HI (US)

(**) Term: **14 Years**

(21) Appl. No.: **29/373,749**

(22) Filed: **May 17, 2011**

(51) **LOC (9) Cl.** 14-01

(52) **U.S. Cl.**

USPC **D14/205**

(58) **Field of Classification Search**

USPC D14/205, 206, 223; 181/129, 130, 135; 379/430, 431; 381/380, 381, 376, 388; 455/90.3, 575.1; 439/668, 669; D13/133; 2/422, 209.13
